ABSTRACT: In a coin sorter in which coins and slugs roll down a runway past a magnet which affects their speeds an anvil is provided above the path of genuine coins leaving the runway, so that is is struck only by slugs which leave the runway at a greater speed than the genuine coins, such slugs bouncing off the anvil into a rejection path which is also followed by slugs which leave the runway at a slower speed than genuine coins, the genuine coins alone following an acceptance path. This is particularly useful in coin sorters which have a separate, parallel runway for all-nickel coins, the latter entering the separate runway via an aperture in a plate and eventually passing through another aperture in the plate to follow the acceptance path. The all-nickel coins are drawn through the first-mentioned aperture by a magnet against the resilient action of a spring-urged gate and stops are provided for limiting both inward and outward swinging movements of the gate.

COIN SORTER ANVIL MOUNTING

BACKGROUND OF THE INVENTION

This invention relates to coin sorters of the type used in vending machines to sort genuine coins from spurious coins, such as steel, brass or copper slugs, and reject the latter for return to the user.

In coin sorters at present in use it is common to have the coins and slugs roll down an inclined runway between plates and past a magnet, thus affecting their speed so that brass slugs, for example, will leave the runway at a higher speed and copper slugs at a lower speed than that at which genuine coins leave the runway. The coins and slugs then strike an anvil and rebound either into an acceptance path, in the case of the genuine coins, or into a rejection path for the slugs.

With the advent of all-nickel coinage in Canada, I invented the device disclosed in my Canadian Pat. No. 722,923, issued Dec. 5, 1967, wherein genuine all-nickel coins are diverted laterally from the runway through an aperture in the plate which is remote from the magnet, roll down a guide on the other side of said plate and are brought back into the path for the other genuine coins through a second aperture in said plate after they have passed the location of the magnet, which otherwise would have stopped them. To facilitate the passage of the all-nickel coins through said second aperture I provided an anvil which was laterally movable but I have now discovered better solution.

BRIEF SUMMARY OF THE INVENTION

Thus, according to the present invention, I provide a coin sorter having a runway down which genuine coins and slugs travel past a magnet and are influenced by the latter so that they leave the end of the runway at different speeds, and an anvil spaced from the end of said runway and disposed above the path of genuine coins passing from the end of said runway into an acceptance path, the anvil being positioned such that slugs leaving the runway at a speed in excess of that at which genuine coins leave the runway will strike the anvil and rebound into a rejection path which is also followed by slugs which leave the runway at a speed slower than that at which genuine coins leave the runway.

By thus departing radically from previous coin sorter constructions I can locate the anvil so that even in its normal position it will not impede the reentry of all-nickel coins into the path followed by other genuine coins. Moreover, I have found that I can form the anvil as part of a sweeper arm which, when actuated, sweeps past the magnet to dislodge anything held by the latter. The sweeper arm is biased upwardly against stop means and said stop means is preferably adjustably mounted to provide for fine adjustment of the normal position of the anvil.

BRIEF DESCRIPTION OF THE DRAWINGS

A presently preferred embodiment of the invention will now be described, by way of example, with reference to the accompanying drawings, in which:

FIG. 1 is a front elevational view of a coin sorter embodying the present invention;

FIG. 2 is a rear elevational view thereof; and

FIG. 3 is a fragmentary part-sectional view of only those parts of the sorter essential for an understanding of the invention.

DETAILED DESCRIPTION

The coin sorter, as shown, has a back mounting plate 1 provided with lugs 2 for mounting it in a vending machine. A large front plate 3 and a small front plate 4 are pivotally mounted on a pivot pin 5 carried in brackets 6 which extend inwardly from a forwardly extending flange 7 on the plate 1, plates 3 and 4 being independently urged toward plate 1 by spring means 8.

Plate 3 carries an inclined runway 9 and plate 4 carries a magnet 10.

A coin chute 11 is mounted at the top of plate 1 and coins fed thereto are led to a cradle 12 which allows smaller coins such as one-cent, five-cent and ten-cent pieces to pass through for sorting lower down in the sorter. A twenty-five cent piece or a slug of the same size will, however, rock the cradle and be deposited on the upper end of runway 9, unless it is a ferrous slug in which case it will be held by a magnet 13 (FIG. 2) pivotally mounted at the back of plate 1 to extend through a small aperture 14 therein. Older type genuine coins, together with nonferrous slugs such as brass and copper, roll down the runway past magnet 10 and their speeds are affected by the latter so that the brass slugs leave the runway at a greater speed and the copper slugs leave the runway at a slower speed than that of the coins. The new type of all-nickel Canadian twenty-five cent piece is drawn through an aperture 15 in the plate 1 by a magnet 16 against the resilient action of a sprung-urged gate 17 and enters a guide 18 secured to the back of plate 1. The bottom of the guide forms a runway for the all-nickel coin and the guide has an inwardly sloping portion 19 which serves to divert the coin through an aperture 20 in plate 1, whereafter it follows the same eventual acceptance path as the other genuine coins.

Referring now to FIG. 3, it will be seen that there is an anvil 21 spaced from the end of the runway 9, the anvil forming the lower terminal portion of a sweeper arm 22 adapted, when actuated, to sweep across the magnet 10 and dislodge anything held thereby between plates 1 and 4. The sweeper arm is actuated by depression of roller 23 which happens when the coin return lever of the vending machine is operated by the user. The roller 23 is rotatably mounted on a member 24 which is pivotally mounted on a pivot pin 25 extending forwardly from back plate 1 and has a forwardly extending intermediate flange 26 and a forwardly extending cam 27, the latter cooperating with a roller 28 (FIG. 1) mounted on the upper end of plate 3 to move the plate 3 away from plate 1 as the roller 23 is depressed, thus moving the runway 9 out of the way of arm 22 as it sweeps between plates 1 and 4.

The sweeper arm 22 is pivotally mounted on pivot pin 29 on the back plate 1 and lies between plate 1 and member 24, the latter having a drive pin 30 which extends rearwardly through a curved slot 31 in the arm 22 to drive the arm as the roller 23 is depressed and to retract the arm as the roller is returned to its normal position shown. The roller 23 and hence the arm 22 are held in normal position by a spring 32 and stop 33. The spring is coiled around pivot pin 25 and has one end extending under an anchor pin 34 on plate 1 and the other end extending under flange 26 on member 24.

The stop 33 is in the form of a substantially rectangular block seated in a shallow recess 35 in the plate 1 and extending forwardly therefrom. The block has two slots 36 therein and two screws 37 extend freely through said slots and are screwed into suitable tapped holes in plate 1. An Allen screw 38 threaded through a tapped hole in a forward projection 39 on plate 1 engages the opposite side of the stop from that engaged by arm 22 and the normal position of the anvil is thus finely adjustable.

As is clearly shown in FIG. 3, brass slugs leave the runway at a sufficiently great speed that they strike the anvil 21 and rebound, as shown, to the left hand side of the separator 40 so that they will follow a rejection path and be returned to the user at the front of the vending machine. Silver-containing coins, on the other hand, leave the runway at a slower speed and the normal position of the anvil is such that they pass underneath it and fall to the right of the separator 40 so that they pass follow an acceptance path. Copper slugs leave the runway at an even slower speed and they, too, fall to the left of separator 40 to be rejected as the brass slugs are. It will also be clear from FIG. 3 that all-nickel coins which leave the runway via the aperture 15 may reenter the space between the plates via the aperture 20 without being impeded by the anvil, since it is for the most part disposed above the aperture.

As clearly shown in FIG. 2, the gate 17 is pivotally mounted on a hinge pin 41 and is urged forwardly by spring 42 coiled around the hinge pin and having one end 43 engaging the back of the gate and the other end 44 engaging the back of plate 1. A stop 45 extends upwardly from the gate to engage the back of plate 1 and prevent the gate from passing forwardly through the aperture 15. A second stop 46 is attached at one end to plate 1 by a screw 47 and extends down behind the stop 45 to limit rearward movement of the gate, as otherwise the gate might swing back too far and allow a coin passing through aperture 15 to come too close to magnet 16 and be slowed down to an undesirable extent.

WHAT I CLAIM AS MY INVENTION IS:

1. A coin sorter having a first runway down which genuine coins and slugs travel past a magnet and are influenced by the latter so that they leave the end of the runway at different speeds, an anvil spaced from the end of said runway and disposed above the path of genuine coins passing from the end of said runway into an acceptance path, the anvil being positioned such that slugs leaving the runway at a speed in excess of that at which genuine coins leave the runway will strike the anvil and rebound into a rejector path which is also followed by slugs which leave the runway at a speed slower than that at which genuine coins leave the runway, a plate having a first aperture upstream of said magnet and a second aperture downstream of said magnet, a second runway on the opposite side of said plate from said first runway, means for diverting coins made of nickel laterally from said first runway through said first aperture to said second runway, and means for diverting said coins made of nickel, after they have passed the magnet, through said second aperture in said plate to terminate in said acceptance path, at least a major portion of said anvil being disposed above said second aperture to avoid impeding coins passing through the latter.

2. A coin sorter as claimed in claim 1, wherein said anvil forms a terminal portion of a sweeping arm which, when actuated, sweeps past said magnet to dislodge anything held by the latter, stop means being mounted in the sorter and means being provided for holding said sweeping arm normally in a position abutting said stop means.
3. A coin sorter as claimed in claim 2, wherein said stop means is adjustably mounted in the coin sorter to enable fine adjustment of the normal position of the anvil.
- 10 4. In a coin sorter wherein coins roll down an inclined runway between plates and past a magnet and genuine coins are separated from spurious coins or slugs in dependence upon their speed on leaving said runway, the improvement which comprises an anvil suspended from a pivot above said runway, resilient means urging said anvil away from the end of said runway, stop means for limiting the movement of the anvil away from the end of the runway, and means mounting said stop means adjustably in the coin sorter, the arrangement being such that slugs leaving the runway at a speed in excess of that at which genuine coins leave the runway will strike the anvil and rebound into a rejection path which is also followed by slugs which leave the runway at a speed below that at which genuine coins leave the runway, genuine coins passing under the anvil into an acceptance path.
- 15 5. A coin sorter as claimed in claim 4, one of said plates having exit means and reentrance means for coins made from nickel, said exit means being disposed upstream of said magnet and said reentrance means being disposed downstream of said magnet, said anvil being mounted with at least a major portion thereof above said reentrance means.
- 20 6. A coin sorter as claimed in claim 5, wherein said anvil forms part of a sweeping arm adapted, when actuated, to sweep past said magnet.
